US00D841335S

(12) **United States Design Patent** (10) Patent No.: **US D841,335 S**
(45) Date of Patent: **** Feb. 26, 2019**

(54) **TOOTHBRUSH**(71) Applicant: **Colgate-Palmolive Company**, New York, NY (US)(72) Inventors: **Eduardo Jimenez**, Manalapan, NJ (US); **Robert Moskovich**, Manakin-Sabot, VA (US); **Michael Rooney**, Millburn, NJ (US); **Joachim Storz**, Zell am See (AT); **Raimund Klausberger**, Vienna (AT); **Andreas Wechsler**, Zell am See (AT)(73) Assignee: **Colgate-Palmolive Company**, New York, NY (US)(**) Term: **15 Years**(21) Appl. No.: **29/639,834**(22) Filed: **Mar. 9, 2018**

CLAIM

The ornamental design for a toothbrush, as shown and described.

DESCRIPTION

FIG. 1 is a right front perspective view of a toothbrush according to a first embodiment of the new design;

FIG. 2 is a left front perspective view thereof;
 FIG. 3 is a right rear perspective view thereof;
 FIG. 4 is a left rear perspective view thereof;
 FIG. 5 is a front elevation view thereof;
 FIG. 6 is a rear elevation view thereof;
 FIG. 7 is a right-side elevation view thereof;
 FIG. 8 is a left-side elevation view thereof;
 FIG. 9 is an enlarged top plan view thereof;
 FIG. 10 is an enlarged bottom plan view thereof;
 FIG. 11 is a close-up view of area 11 of FIG. 1;
 FIG. 12 is a close-up view of area 12 of FIG. 2;
 FIG. 13 is a close-up view of area 13 of FIG. 3;
 FIG. 14 is a close-up view of area 14 of FIG. 4;
 FIG. 15 is a close-up view of area 15 of FIG. 6;
 FIG. 16 is a close-up view of area 16 of FIG. 7;
 FIG. 17 is a close-up view of area 17 of FIG. 8;
 FIG. 18 is a right front perspective view of a toothbrush according to a second embodiment of the new design;
 FIG. 19 is a left front perspective view thereof;
 FIG. 20 is a right rear perspective view thereof;
 FIG. 21 is a left rear perspective view thereof;
 FIG. 22 is a front elevation view thereof;
 FIG. 23 is a rear elevation view thereof;
 FIG. 24 is a right-side elevation view thereof;
 FIG. 25 is a left-side elevation view thereof;
 FIG. 26 is an enlarged top plan view thereof;
 FIG. 27 is an enlarged bottom plan view thereof;
 FIG. 28 is a close-up view of area 28 of FIG. 18;
 FIG. 29 is a close-up view of area 29 of FIG. 19;
 FIG. 30 is a close-up view of area 30 of FIG. 20;
 FIG. 31 is a close-up view of area 31 of FIG. 21;
 FIG. 32 is a close-up view of area 32 of FIG. 23;
 FIG. 33 is a close-up view of area 33 of FIG. 24; and,
 FIG. 34 is a close-up view of area 34 of FIG. 25.

The dotted lines illustrate portions of the article that form no part of the claimed design. The long-short dashed broken lines shown on the article illustrate the bounds of the claimed design and form no part thereof. The circles shown in the long-short dashed broken lines illustrate the bounds of the enlarged detail views and the portions of the figures from which they were taken and form no part of the claimed design.
